UNITED STATES PATENT OFFICE.

JOHN H. AULT AND JOHN T. HEATON, OF CHICAGO, ILLINOIS.

THROTTLE-OPERATING MECHANISM.

1,331,408.

Specification of Letters Patent. Patented Feb. 17, 1920.

Application filed March 21, 1918. Serial No. 223,795.

To all whom it may concern:

Be it known that we, JOHN H. AULT and JOHN T. HEATON, citizens of the United States, and residents of the city of Chicago, county of Cook, and State of Illinois, have invented certain new and useful Improvements in Throttle-Operating Mechanisms, of which the following is a specification.

The invention relates to improvements in throttle operating mechanisms, especially adapted for use on Ford automobiles and arranged to permit of both hand and foot control of the throttle valve of the engine.

The invention consists in the combinations and arrangements of parts hereinafter described and claimed.

The invention will be best understood by reference to the accompanying drawings forming a part of this specification, and in 20 which,

Figure 1, is a sectional view illustrating an engine control embodying the invention in position of use,

Fig. 2, a diagrammatic plan view of the 25 engine control proper,

Fig. 3, a detailed view of a control rod employed in the construction, and

Fig. 4, an enlarged section taken on line 4-4 of Fig. 3.

The preferred form of construction as 30 illustrated in the drawings, comprises a control rod 5 operatively connected at one end with the throttle valve lever 6 of the carburetor 7 of the engine. A sleeve 8 is slidably mounted on the other end of rod 5 and a bell crank lever is pivoted at 8' on said sleeve, one arm 9 of said bell crank lever being pivotally connected with one end of 35 a link 10 having an eye 11 at its other end sliding freely on rod 5. The movement of eye 11 in one direction is limited by a cotter pin 12 passed through the rod 5 and a compression spring 13 is imprisoned between said cotter pin and the sleeve 8. The sleeve 40 8 is provided with a depending arm 14 which limits the swinging of the bell crank arm 9 on one direction, and thus limits the movement of sleeve 8 on rod 5 in one direction.

The other arm 15 of the bell crank lever 45 is connected by an operating rod 16 with a crank 17 and formed at one end of a crank shaft 18 equipped with bearings 19 arranged to be secured to the under side of the foot-board of the automobile. Another crank 21 50 is formed at the other end of shaft 18 and carries a foot pin 22 pivotally connected

therewith and arranged to operate through a hole in the foot-board 20 and by means of which the crank shaft 18 may be readily operated to oscillate bell crank 15 to operate 60 the control rod 5 to operate the throttle 6 of the carburetor 7.

The sleeve 8 is provided with an integral extension 23 pivotally connected to one end of a pin 24 arranged to be pivotally connected to the free end of an oscillatory arm 25 fixed to the usual oscillatory shaft 26 mounted on the steering post 27 and associated with the steering shaft 28 of the automobile, said shaft 26 being equipped with 70 the usual operating arm at the upper end of the steering post for controlling the throttle valve of the engine. By this arrangement oscillation of shaft 26 causes retraction of the sleeve 8, and consequently of rod 5 to 75 operate the throttle valve of the engine, owing to the fact that the oscillation of lever arm 9 is limited by stop 14, so that, in effect, a rigid connection is effected between said sleeve and rod 5 for movement in this direction.

It will thus be observed that the throttle valve of the engine may be readily controlled by manipulating the usual oscillating shaft 26 or by operating the foot pin 22 and 85 that each operates independently of the other. The arrangement is such that the attachment may be readily substituted for the control rod now in use on Ford automobiles by a slight bend in the arm 25 90 with which said automobiles are ordinarily equipped. The specific form of arrangement of parts is a simple and efficient one for the purpose.

While we have illustrated and described 95 the preferred form of construction for carrying the invention into effect, this is capable of variation and modification without departing from the spirit of the invention. We therefore do not wish to be limited to 100 the precise details of construction set forth, but desire to avail ourselves of such variations and modifications as come within the scope of the appended claims.

Having described our invention, what we 10 claim as new and desire to secure by Letters Patent is:—

1. The combination with the throttle of a carburetor of an engine, of a control rod attached at one end to said throttle; a sleeve 11 11 slidable on the other end of said rod; a bell crank lever pivotally mounted on said

sleeve; a link pivotally connected with one arm of said bell crank lever and slideable on said rod; a pin extending through said rod and limiting movement of said link thereon 5 in one direction; a compression spring imprisoned between said pin and said sleeve; a stop on said sleeve limiting the movement of said arm of said bell crank; an operating rod pivotally connected with the other arm 10 of said bell crank; a crank shaft arranged to be mounted on the under side of the foot-board of an automobile and provided with a crank at each end, the crank at one end being pivotally connected with said operating rod; a foot pin pivotally connected with the other crank and arranged to operate through an opening in said foot board; a steering post for the automobile; an oscillating shaft on said steering post; an oscillating arm on said shaft; and an operative 15 connection between said oscillating arm and said sleeve, substantially as described.

2. The combination with the throttle valve of a carburetor of an engine, of a control rod attached at one end to said valve; a sleeve slideable on the other end of said rod; a bell crank lever pivotally mounted on said sleeve; a link pivotally connected with one arm of said bell crank lever and slideable 20 on said rod; means for limiting the movement of said link thereon in one direction; a compression spring interposed on said rod between said means and said sleeve; a stop on said sleeve limiting the movement of said 25 arm of said bell crank; an operating rod pivotally connected with the other arm of said bell crank; pedal means for operating the said rod; a steering post for the automobile; an oscillating shaft on said steering 30 post; an oscillating arm on said shaft; and an arm integral with and extending from said sleeve and pivotally connected at one end with said oscillating arm, substantially 35 as described.

the said rod; a steering post for the automobile; an oscillating shaft on said steering post; an oscillating arm on said shaft; and an arm extending from said sleeve and pivotally connected with said oscillating arm, 40 substantially as described.

3. The combination with the throttle valve of a carburetor of an engine, of a control rod attached at one end to said valve; a sleeve slideable on the other end of said rod; a bell crank lever pivotally mounted on said sleeve; a link pivotally connected with one arm of said bell crank lever and slideable 45 on said rod; means for limiting the movement of said link thereon in one direction; a compression spring interposed on said rod between said means and said sleeve; a stop on said sleeve limiting the movement of said 50 arm of said bell crank; an operating rod pivotally connected with the other arm of said bell crank; pedal means for operating the said rod; a steering post for the automobile; an oscillating shaft on said steering 55 post; an oscillating arm on said shaft; and an arm integral with and extending from said sleeve and pivotally connected at one end with said oscillating arm, substantially 60 as described.

In testimony whereof we have signed our names to this specification in the presence of two subscribing witnesses.

JOHN H. AULT.
JOHN T. HEATON.
